THE NORRIS PETERS CO., WASHINGTON, D. C.

UNITED STATES PATENT OFFICE.

WALTER J. HERSCHEDE, OF CINCINNATI, OHIO.

BELL-RACK FOR HALL-CLOCKS.

988,338.

Specification of Letters Patent.

Patented Apr. 4, 1911.

Application filed May 9, 1908. Serial No. 431,813.

To all whom it may concern:

Be it known that I, WALTER J. HERSCHEDE, a citizen of the United States of America, and resident of Cincinnati, county of Hamilton, State of Ohio, have invented certain new and useful Improvements in Bell-Racks for Hall-Clocks, of which the following is a specification.

The object of my invention is a rack which will maintain the bells in their proper relative position both to the clock frame and to the bell hammers and which is also simple and comparatively small and inconspicuous.

Referring to the accompanying drawings forming a part hereof, Figure 1 is a perspective view of the top of a clock of the form for which my bell rack is especially adapted. Fig. 2 is a sectional view of the top of a clock case upon lines $x-x$ of Fig. 1, the case for the works being shown in side elevation. Fig. 3 is a perspective view of the rack upon an enlarged scale, the frame of the rack being broken out and the parts brought together to economize space. Fig. 25 4 is a sectional view taken upon line $v-v$ of Fig. 3.

It has been customary to support the tubular bells of hall clocks upon a bar which was held between the upper ends of uprights, which extended down and were secured to the narrower portion of the clock case. Another way of mounting the tubular bells was to suspend them from an arm, which had downwardly projecting arms, 35 which were bent inwardly and secured to the back of the clock case. The objections to the first of these forms are that the arm, from which the bells are hung, being at such a distance from the points where the 40 uprights were secured to the sides of the clock case, the arm is apt to change its relative position to the clock case and to the hammers, thereby throwing the hammers out of adjustment with the bells. Another 45 objection to this form of rack is that it is large and conspicuous, a feature especially objectionable in cases having glass sides. Still another objection to this form of rack is that it is not adjustable for different size 50 cases. The objection to the form of rack which is attached to the back of a clock is that the warping of the back changes the relative position of the rack in the case, thus destroying the adjustments of the hammers 55 and the bells.

In my invention the rack consists of a metallic frame made of a horizontal top bar, A, having downturned ends, a , a' , and a horizontal bar, A'. From the end, a' , there are two horizontal forwardly projecting studs, a^2 , a^3 . Bar, A, has the usual pins, a^4 , from which tubular bells, B, are suspended. Bells, B, constitute the chimes. Upon bar, A', the spring-arms, c , which carry the hammers, C, at their upper ends, 60 are secured in alinement with the bells, B. From stud, a^2 , the hour bell, D, is suspended and upon the stud, a^3 , spring-arm, d , for carrying the hour hammer is secured.

The frame of the rack has secured to the 70 top of its sides adjustable brackets, E, E', the ends, e , e' , of which may be turned either upward or downward, as illustrated in full, and dotted line, in Fig. 3. The brackets are made adjustable by having in them longitudinal slots, e^2 , e^3 , which register with slots in the top of the frame and in the top of angle pieces, e^4 , e^5 , which are secured to the sides of the frame. Through the slots are passed bolts, e^6 , which may be loosened for 80 adjusting the brackets, E, E', inward or outward to fit different widths of clock case. The arms, e , e' , of the brackets are secured to the tops of the sides, g , of the clock case, 85 G, adjacent to the back of the case.

H, is the case containing the clock works.

Since the bar from which the bells are suspended is so close to the point at which the rack is secured to the clock case, there is little chance for the relative position of the bells and the case varying and for the relative position of the hammers and the bells varying. By reason of the small space taken up by the frame of the rack, and likewise of its being hung to the top and rear of the clock case, the construction is one of especial advantage in 90 clocks which have glass sides, such as g' , in Figs. 1 and 2, wherein the rack is not seen to any extent from the exterior of the clock.

What I claim is:

1. In combination with a clock case, a rack for suspending tubular bells in the case consisting of a frame, brackets secured to the top of the frame and the sides of the clock case, and means for adjusting the brackets to the width of the clock case and of securing them to the frame. 105
2. In combination with a clock case, a rack for supporting tubular bells in the case consisting of a frame, means of suspending the 110

5 bells from the frame, brackets secured to the sides of the case, each bracket being provided with a slot, and bolts, secured to said frame and engaging the slots to suspend said frame and secure it to the sides of the case.

10 3. In combination with a clock case, a rack for suspending tubular bells in the case, consisting of a frame provided with means for suspending the bells, and means for mounting the striking hammers, mounting brackets for said frame secured to the sides of the clock case and provided with longitudinally extending slots and bolts secured to said

frame, which engage said slots to adjustably secure said frame to said brackets. 15

4. In combination with a clock case, a rack for suspending bells in the case consisting of a frame, means for suspending the bells from said frame, brackets secured to the top 20 of the frame and the sides of the clock case, a slot provided in each bracket and bolts for engaging said slot and securing said rack to said bracket.

WALTER J. HERSCHEDE.
